UNITED STATES PATENT OFFICE.

BENJIMIN F. HALEY, OF WEST PALM BEACH, FLORIDA.

RABBETING PLANE.

Application filed January 10, 1925. Serial No. 1,670.

To all whom it may concern:

Be it known that I, BENJIMIN FRANKLIN HALEY, a citizen of the United States, residing at West Palm Beach, in the county 5 of Palm Beach and State of Florida, have invented certain new and useful Improvements in a Rabbeting Plane, of which the following is a specification.

This invention relates to new and useful improvements in wood working tools 10 and is more particularly adapted to a plane for forming grooves or slots in woodwork in which grooves or slots are adapted to be secured hinges, locks, flush plates and the 15 like.

One of the important objects of the present invention is to provide a rabbeting plane wherein means are provided for adjusting the cutting depth of the cutter, means being further provided for facilitating the 20 positioning of the cutter member on either side of the bed plate of the plane.

A further object is to provide a rabbeting plane of the above mentioned character, 25 which is simple in construction, inexpensive, strong and durable and furthermore adapted for the purposes for which it is designated.

Other objects and advantages of this invention will become apparent during the 30 course of the following description.

In the accompanying drawing forming a part of this specification and in which like numerals designate like parts throughout 35 the same:

Figure 1 is a top plan view of the rabbeting plane embodying my invention, and

Figure 2 is a side elevation thereof.

In the drawing wherein for the purpose of 40 illustration is shown the preferred embodiment of my invention, the numeral 1 designates the bed plate or stock of my improved rabbeting plane, the same being provided with the cut out portion 2 therein whereby 45 the plane is rendered light in weight. The usual handles or knobs 3 are secured at their respective ends of the bed plate. An up- 50 standing block 4 is secured on the bed plate 1 adjacent the forward end thereof, the same being spaced equally from the side edges of the bed plate as clearly illustrated in Figure 1. The block is provided with the vertically extending substantially V-shaped 55 grooves 5 and 6 in the front and rear faces thereof respectively, the same cooperating at the lower end of the block with the ad-

jacent ends of the cut out portions provided in the bed plate and which are also V-shaped. The purpose of this construction will hereinafter be more fully described. 60

Adapted to be secured on either side of the block 4 by means of the screws 7 is the tool post designated generally by the numeral 8. The outer end of the tool post is adapted to extend beyond the side edge 65 of the bed plate 1 and is formed in its front and rear faces with the substantially V-shaped vertically extending slots 9 and 10 respectively.

The shank 11 of the cutting tool 12 is 70 substantially rectangular in cross section and is adapted to be disposed within the V-shaped slot 9 formed in the front face of the outwardly extending portion of the tool post 8. A clamp such as is shown at 13 extends around the outer portion of the tool post and the adjacent portion of the shank 11 of the cutting tool and a set screw or the like illustrated at 14 is associated with the rear end of the clamp, the inner end of the 75 set screw being adapted to be received within the V-shaped notch or slot 10 whereby the clamp 13 may be brought into locked engagement with the shank 11 of the tool and the tool post for holding the tool in its various vertically adjusted positions. It is of course to be understood that the shank 11 of the tool is adapted for slidable movement within the V-shaped slot 9 so that the cutting depth may be regulated and adjusted. 80

When in position, the edge 12 of the tool will be disposed adjacent the side edge of the bed plate and the plane actuated in the manner well known in the art for the purpose of forming a longitudinal groove or channel in the woodwork. By removing the screws 7, the tool post 8 may be detached from one side of the block 4 and secured on the opposite side so that a cutting tool may be supported on the opposite side edge of the bed plate, thus enabling the plane to be used from either the left or the right hand side. Also, by entirely detaching the tool post 8, and placing the shank 11 of the tool in the V-shaped slot 5 formed in the front face of the block 4, the cutting edge 12 will be disposed within the cut out portion 2 of the bed plate so that the tool will be disposed in the intermediate portion 95 of the bed plate. The clamp 13 will be placed around the block 4, the forward por- 100

105

110

tion thereof engaging the shank portion 11, while the set screw will engage the V-shaped slot 6 as is obvious from the construction illustrated.

5 It will thus be seen from the foregoing description, that a rabbeting plane has been provided wherein the parts are of such construction as to enable the same to be readily assembled and adjusted without the loss of 10 any considerable time or labor and will further at all times be positive and efficient in carrying out the purposes for which the same has been designated.

15 While I have shown the preferred embodiment of my invention, it is to be understood that various changes in the size, shape and arrangement of parts may be resorted to without departing from the spirit of the invention and the scope of the appended claims.

20 Having thus described the invention, what I claim is:—

1. A rabbeting plane comprising in combination, a bed plate, a block secured thereon and spaced from the side edges thereof, a tool post, means for detachably supporting it on either side of said block, the outer portion thereof being disposed beyond the side edge of the bed plate, and a clamp for detachably and adjustably securing a tool thereon.

2. A rabbeting plane comprising in combination a bed plate, a block secured thereon and spaced from the side edges thereon

of, a tool post, means for detachably supporting it on either side of said block, the outer portion thereof being disposed beyond the side edge of the bed plate, the outwardly extending portion of the tool post being provided in its front face with a vertically extending substantially V-shaped groove, for receiving the shank portion of a cutting tool, and means for detachably and adjustably securing the shank of the tool in said groove.

3. A rabbeting plane comprising in combination, a bed plate, a block secured thereon and spaced from the side edges thereof, a tool post, means for detachably supporting it on either side of said block, the outer portion thereof being disposed beyond the side edge of the bed plate, the outwardly extending portion of the tool post being provided in its front face with a vertically extending substantially V-shaped groove, for receiving the shank portion of a cutting tool, means for detachably and adjustably securing the shank of the tool in said groove, said means comprising a clamp adapted to extend around the outer portion of the tool post and the shank of the tool, and a set screw associated with the rear end of the clamp and adapted for engagement with the rear face of the outer portion of the tool post.

65 In testimony whereof I affix my signature.

BENJIMIN F. HALEY.
